UNITED STATES PATENT OFFICE

EDWARD J. SHOEMAKER, OF CANTON, OHIO

SUBMARINE AND AUXILIARY BOAT THEREFOR

Application filed February 7, 1928. Serial No. 252,469.

My invention relates to submarines and to auxiliary boats which are releasably secured in docks in the submarines, and adapted for navigation to and from the docks either independently of or connected with the submarines.

It is desirable that such an auxiliary boat for a submarine should be associated with the submarine in such a way that it may be manned by a part of the submarine's crew and be able to carry out missions independently of the submarine, by being released from its dock either when the submarine is at the surface or submerged, by being navigated away from the submarine for the purpose of accomplishing its mission which may be for example surface scouting or making a landing on enemy territory, and by being navigated back to and resecured in its dock in the submarine.

Such an auxiliary boat should also be adapted to be occupied by the commanding officer of the submarine while the submarine is submerged, to be released from its dock, to come to the surface, to be physically connected with the submarine in such a manner that the commanding officer may make observations at the surface and direct the maneuvering of the submarine and control the firing of its torpedoes, and then to be redocked in the submarine.

Finally, such an auxiliary boat should be adapted to be used as a life boat which may be occupied by, and rescue part or all of, the crew of a submerged submarine which is incapable of coming to the surface; and, if the engine room or other communicating compartments of the submerged and disabled submarine are not flooded, the auxiliary boat should also be adapted for use in providing for these compartments a supply of fresh air and compressed air for sustaining life and preventing flooding.

Auxiliary boats which have heretofore been suggested have not been capable of functioning in the above described manner; and the objects of the present invention include the provision of a submarine and an auxiliary boat associated with each other for functioning as aforesaid.

Further objects of the present improvements include the provision of a novel submarine and auxiliary boat as aforesaid, and in which the cooperating parts thereof are so constructed and arranged as to render their operation certain and effective.

The improvements comprising the present invention include accordingly constructions and arrangements for a submarine and auxiliary boat adapted for attaining the foregoing and ancillary objects, and further include details of construction of the cooperating parts thereof.

A preferred embodiment of these improvements is hereinafter set forth in detail, and is illustrated in the accompanying drawings forming part hereof, in which—

Figure 1 is a top plan view illustrating a submarine and one of the improved auxiliary boats docked therein;

Fig. 2, an elevation view with portions in section illustrating the auxiliary boat about to be docked in the submarine;

Fig. 3, a fragmentary top plan view illustrating an improved bumper for use in docking the auxiliary boat;

Fig. 4, a fragmentary sectional view thereof as on line 4—4, Fig. 3;

Fig. 5, an enlarged fragmentary view similar to Fig. 1;

Fig. 6, a fragmentary sectional view thereof of longitudinal of the auxiliary boat as on line 6—6, Fig. 5, the auxiliary boat and cooperating apparatus in the submarine being illustrated in side elevation;

Fig. 7, a transverse fragmentary sectional view thereof as on line 7—7, Fig. 5, the auxiliary boat and cooperating apparatus in the submarine being illustrated in end elevation;

Fig. 8, an enlarged transverse fragmentary sectional view of the submarine and the auxiliary boat, as on line 8—8, Fig. 6 and Fig. 11;

Fig. 9, a similar view as on line 9—9, Fig. 6 and Fig. 11;

Fig. 10, a similar fragmentary transverse sectional view illustrating a water by-pass in the auxiliary boat;

Fig. 11, an enlarged fragmentary sectional view similar to Fig. 6, in which parts of the

connecting apparatus in the submarine are illustrated in section;

Fig. 12, a fragmentary end elevation thereof as on line 12—12, Fig. 11;

Fig. 13, a fragmentary sectional view thereof as on line 13—13, Fig. 11;

Fig. 14, a fragmentary elevation view of the cable connecting the submarine and auxiliary boat, portions of the several walls thereof being broken away;

Fig. 15, a transverse sectional view thereof as on line 15—15, Fig. 14;

Fig. 16, an enlarged fragmentary view similar to Figs. 6 and 11, with portions in sections, and more clearly illustrating details of the stabilizing hitch between the cable and the auxiliary boat;

Fig. 17, a fragmentary transverse sectional view thereof as on line 17—17, Fig. 16; and

Fig. 18, a fragmentary transverse sectional view thereof as on line 18—18, Fig. 16.

Similar numerals refer to similar parts throughout the drawings.

The submarine indicated generally at 10 includes, in combination with the usual structure, operating machinery and controls of a submarine, water-sealed walls forming a dock 11 opening outwardly preferably from the upper deck 12 of the submarine; and one 25 of the dock walls is provided with an opening 13 therein communicating with the interior of one of the water-tight compartments 14 of the submarine, and a door 15 swinging into the compartment 14 is arranged for water-30 sealing the opening 13.

The upper deck plates 16 project inwardly over the upper edges of the side and end walls of the dock 11, and flanges 17 are secured to the inwardly projecting portions of the plate 40 16, the upper surface of the flanges 17 abutting against the lower surfaces of the plate 16, and the flanges 17 projecting inwardly beyond the inner edges of the plates 16, forming a rabbeted seat 18 for the auxiliary boat.

The flanges 17 are preferably legs of angles, the other legs 19 of which are secured to the side and end walls of the dock 11.

At spaced intervals between the legs 17 and 50 19, clamping seats 20 are provided, and will hereinafter be set forth in greater detail.

An auxiliary submarine boat 21 is arranged to be secured in the dock 11, and to provide a water-sealed closure for the opening thereof.

Sealing flanges 22 extend outwardly preferably from the intersection of the upper edges of the hull 23 and the outer edges of the deck plates 24 of the auxiliary boat; and the outwardly extending sealing flanges 22 60 are arranged to overlap the inwardly extending dock flanges 17.

A sealing gasket 25 preferably of resilient material such as rubber, is carried on the upper surface of the dock flanges 17 and is arranged to be compressed against the lower

surfaces of the sealing flanges 22 to provide a water-sealed closure for the upper opening of the dock.

Improved means for effecting this water-sealed closure include internally threaded sleeves 26 spaced within the auxiliary boat 21 70 at intervals corresponding with the intervals of the clamping seats 20 at the upper edges of the dock.

A screw 27 is screwed in each of the sleeves 26, the axes of the sleeve being preferably angled upwardly, and the outer end 28 of each screw extending outwardly and upwardly from the hull 23 of the auxiliary boat and adapted for clamping and sealing abutment 80 against the suitably angled abutment surfaces 29 of the clamping seats 20 when the screws 27 are screwed outwardly from the interior of the auxiliary boat as by means of hand wheels 30 provided at the inner ends of 85 the screws.

The outer ends 28 of the screws are preferably provided with outwardly extending flange heads 31 preventing withdrawal of the screws inwardly from the sleeves 26, thereby preventing the entrance of water into the interior of the auxiliary boat through the sleeves 26.

For facilitating docking of the auxiliary boat 21 in the dock 11, the submarine is 90 provided with a yielding bumper 32, which may include a frame 33 secured to the rear wall 34 of the submarine conning tower 35, and the frame 33 is preferably formed of shaped plate material provided with vertically extending outwardly opening V walls 36 and 36'.

Bumper plates 37 and 37' are yieldingly secured upon the V walls 36 and 36' respectively, as by means of headed bolts 38 the 100 ends of which extend outwardly through suitable apertures in the plates 36 and 36' and through compression springs 39 and are then secured in the bumper plates 37 and 37', whereby a yielding V bumper is provided for the prow of the auxiliary boat 21, for use in docking the auxiliary boat in the dock 11 of the submarine upon the return of the auxiliary boat to the submarine from an independent mission, as will hereinafter be described in greater detail.

For facilitating releasing of the auxiliary submarine boat from the dock 11, a plurality of jack screw seats 40 are secured to the bottom wall of the dock beneath the position of the keel 41 of the auxiliary boat when the same is secured in the dock; and a plurality of jack screws 42 are screwed in jack nuts 43 mounted within the auxiliary boat; and the outer end 44 of each jack screw 42 extends outwardly from and below the keel of the auxiliary boat and is preferably in the shape of an enlarged spherical head arranged to fit in a suitable spherical socket in its operating jack seat 40. The inner end of 120 125 130

each jack screw 42 within the auxiliary boat is provided with a suitable hand wheel 45 for turning the screw.

The auxiliary boat 21 is provided with an inwardly opening water-sealing man hole door 46 located adjacent the door 15 when the auxiliary boat 21 is docked in the submarine.

The upper deck 24 of the auxiliary boat is likewise provided with a water-sealing man hole door 47, and suitable glass covered water-sealed port holes 48 are provided in the hull 23 of the auxiliary boat.

A by-pass conduit 49 provides a communication through one side of the hull 23 to and through the upper deck thereof, and a valve 50 is provided in the conduit 49 for opening and closing the conduit from within the boat 21.

The auxiliary boat 21 is provided with a rudder 51 controllable from within the boat and a propeller 52 operated as by an electric motor and storage battery mounted in a usual manner within the auxiliary boat.

A water conduit 53 communicates from the dock 11 to any desired water pump not shown within the submarine.

The auxiliary boat 21 associated as aforesaid with the submarine 10, is capable of being carried by the submarine in its maneuvers, of being released therefrom, of carrying out an independent mission, and of being redocked therein, as will hereinafter be set forth in greater detail.

For increasing the co-operative abilities of the auxiliary boat and submarine, they are connected with each other by an extensible and retractable connecting member, indicated generally at 54, the upper end of which is releasably secured to the auxiliary boat, and which passes through a water-sealing opening, indicated generally at 55, into the submarine interior, and the inner end of which is there connected with means, indicated generally at 56, for extending and retracting the connecting member 54.

The extensible and retractable connecting member 54 is preferably in the form of a composite cable which preferably includes a steel cable 57, a plurality of conduits 58, and a plurality of electrical conductor cables 59, all embedded in suitable resilient material 60, and engirdled first by a flexible metallic sheath 61 then by a water proof covering 62 about the sheath 61 and then by a wire wrapping 63 about the sheath 62.

The upper end of the steel cable 57 diverges from the composite cable 54 as at 64, and extends therefrom a substantial distance; and the extremity 65 of the steel cable 57 is secured to a metallic releasing connector 66, the upper end of which is preferably square in cross section and fits into a downwardly opening square aperture provided in the aux-

iliary boat keel at the vertical axis of buoyancy of the auxiliary boat.

A connecting screw 67 extends from the interior of the auxiliary boat 21 into the square aperture and is adapted to be screwed into a suitably threaded aperture in the releasing connector 66; and the screw 67 has secured thereon a shoulder 68 rotatable in a bearing housing 69 mounted within the auxiliary boat, and the upper end of the connecting screw 67 extends within the auxiliary boat and is provided with a hand wheel 70 for turning the same to secure or release the cable connector 66.

The dock 11 is preferably provided with a centrally located sump 71, in the bottom wall of which is provided the water sealing opening 55 through which the composite connecting cable 54 passes to the submarine interior.

The water sealing opening 55, preferably includes a tube 72 depending from the bottom wall of the sump 71, and provided with a stuffing box 73 at its upper end and a stuffing box 74 at its lower end, and through central openings in each of which the cable connecting member 54 extends.

Intermediate the stuffing boxes 73 and 74, a gate valve 75 is provided for closing the opening through the tube 72 if the cable connecting member 54 should accidentally break.

A screw pressure pump 76 likewise communicates with the interior of the tube between the stuffing boxes 73 and 74 and is arranged to provide an oil or grease seal about the cable 54 passing therethrough.

For maintaining the alignment of the cable 54 as it passes through the water sealing opening 55, a set of pulleys 77 and 77^a is secured above and below the tube 72. The outer edges of each set of pulley peripheries roll against each other, and each pulley is provided with a groove therein of semi-circular cross section; and the pulleys being rotatable on horizontal axes, the circular openings thus formed between each set of pulley grooves on the plane through the pulley axes are aligned with the openings of the stuffing boxes 73 and 74.

A rotatable drum 78 is operatively mounted within the compartment 14 and the cable connecting member 54 is wrapped in a suitably dimensioned helical groove 79 on the outer surface of the drum, the lower extremity 80 of the steel cable 57 being rigidly secured to one end 81 of the hoisting drum. The conduits 58 are preferably two in number and arranged for delivering a supply of fresh air from the submarine to the auxiliary boat, or vice versa; and the lower extremity 82 of one of the conduits 58 may be connected with a valve 83 secured on one of the ends of the drum 78, and that conduit 58 may be an air return line.

The drum 78 is mounted on and for rotation with, a tubular axle 84, and the lower extremity 85 of the other conduit 58 is connected

through an improved coupling 86 and the pipe line 87 having a suitable valve 88 therein, to an air pump not shown, and this conduit 58 may thus be an air delivery line.

The improved coupling 86 includes a nipple 89 removably secured in one end of the tubular axle 84, the protruding end 90 of the nipple being connected with the extremity 85 of one of the cable conduits as aforesaid.

One threaded end of a tube 91 is screwed 10 in the outer end of the nipple 89 and secured against rotation as by means of a key 92.

A flange sleeve 93 is slidably mounted on the tube 91, and the inner end of the flange sleeve is provided with a stuffing box 94 for making a closure about the tube 91.

The outer end of the tube 91 is provided with an outwardly extending flange 95, the inner face of which abuts against the outer face of an outwardly extending flange 96 of 20 the flange sleeve 93.

The outer face of the flange 95 abuts against the outwardly extending inner face of an L flange 97 which is connected to the valve 88 as aforesaid.

25 The L flange 97 includes a longitudinally extending outer leg internally threaded and screwed upon external threads on the outer peripheral face of the flange sleeve 93.

Oil grooves 98 are preferably provided in 30 the outwardly extending faces of the flange 95 of the tube 91.

The tube 91 rotates with the axle 84, and the remaining parts of the coupling are stationary.

35 The ends of the axle 84 are journalled in bearing brackets 99, the lower ends of which fit in longitudinal guide rails 100^a and 100^b for longitudinally sliding the drum to maintain the winding or unwinding composite cable 54 in alinement with the openings through the pulleys 77^a and 77^{a'}.

The drum 78 may be operated by an electrical motor 101 geared therewith, and the motor being likewise geared with a screw 45 shaft 102 operating in a threaded nut 103 secured to the floor 104 of the compartment 14, whereby rotation of the motor not only turns the drum, but turns the screw 102 to longitudinally move the drum for maintaining the cable 54 in alinement as aforesaid.

The electrical cables 59 may be three in number, one for providing a telephone circuit, another for providing an electric light circuit, and another for providing a bell or other signal circuit.

55 The cables 59 may extend into and through the tubular axle 84 and terminate at the axle end opposite the coupling 86 at an electrical 50 distributor 105 of any well known construction for completing the desired circuits.

Beyond the divergence of the steel cable 57 therefrom, the upper end of the cable 54 is secured within a piston sleeve 106 which is 65 slidably fitted within a cylinder 107 extend-

ing upwardly from a corresponding aperture in the bottom of the hull 23.

The upper end of the cable 54 is secured within the sleeve 106 in such a way as to provide a water-tight closure for the opening in 70 the sleeve 106, as by means of a ring flange 108 sealed entirely around its inner periphery to the outer periphery of the cable 54, and sealed entirely around its outer periphery with the interior surface of the sleeve 75 106.

The upper end of the sleeve 106 is provided with a packing closure 109 through which pass the several conduits 58 and conductors 59, the joints between the conduits and conductors and the packing closure being water-sealed.

A stop ring flange 110 is provided adjacent the upper end of the cylinder 107, and the sleeve 106 may rise and fall in the cylinder 85 107 when the auxiliary boat 21 is rolling, there being a suitable amount of slack provided in the conduits and conductors above the closure 109 for this purpose.

The cable 54 is sufficiently rigid to maintain the sleeve within the cylinder when the boat 21 is secured within the dock 11.

A gate valve 111 is provided at the upper end of the cylinder 107 for closing the opening of the same when the sleeve 106 has been 95 dropped from the cylinder.

The conduits 58 and conductors 59 extend through suitable openings in the cylinder 107 into the interior of the auxiliary boat 21, where the conductors may then be connected with the desired electrical apparatus and where the conduits may act as supply and return air ducts as aforesaid.

A stabilizing hitch indicated generally at 112 is provided between the cable 57 and the auxiliary boat 21, for assisting in maintaining the auxiliary boat on an even keel when the submarine is submerged and the auxiliary boat is rising therefrom. Under such conditions the buoyancy of the auxiliary boat tends to stretch the cable between its connection within the submarine and its connection with the auxiliary boat by the connector 66.

The stabilizing hitch includes a tubular 115 piston strut 113 slidable up and down within a water-sealed sleeve 114 in the bottom of the submarine hull, the upper end of the piston strut 113 being within the interior of the auxiliary boat and being provided with a handle 115 for raising and lowering the strut, and the lower end of the strut being located outside of and below the auxiliary boat hull.

A swinging hook 116 is secured to the floor of the auxiliary boat and arranged to releasably secure the handle 115 in the position illustrated in full lines in Fig. 16, whereby the piston strut 113 is extended its full length below the bottom of the auxiliary boat.

At the lower end of the piston strut 113, a pair of cooperating jaws 117 and 117' are pivotally mounted on pivot pins 118 and 118', respectively.

5 The jaws 117 and 117' extend downwardly below the pins 118 and 118' and are provided, respectively, at their lower extremities with semi-cylindric notches 119 and 119' arranged to close about a pin 120 extending laterally from a slidable collar 121 through which the cable 57 extends.

From the opposite side of the collar 121 a pivot bolt 122 extends laterally and provides a pivotal mounting for the lower ends 15 of diagonal struts 123 and 123' extending upwardly therefrom and provided at their upper ends, respectively, with U hangers 124 and 124' longitudinally slidable, respectively, on tracks 125 and 125' depending from the 20 keel of the auxiliary boat.

The upper ends of the jaws 117 and 117' extend upwardly and inwardly above the pivot pins 118 and 118', respectively, for engagement in a neck between a lower spherical 25 extremity 126 and the body of a rod 127 slid- 30 able up and down within the tubular strut 118.

The upper end of the rod 127 is externally threaded and screwed in internal threads provided in the upper end of the strut 113, and the rod 127 extends beyond the upper end 35 of the strut 113 and is provided with a suitable hand wheel 128 for turning to raise and lower the rod, whereby the jaws 117 and 117' 40 may be oscillated about the pivot pins 118 and 118', respectively, for opening and closing about the pin 120.

A swinging hook 129 depends from the lower surface of the auxiliary boat deck 24 45 for engagement when desired with the hand wheel 128 to maintain the tube strut 113 in elevated position as illustrated in full lines in Fig. 8.

Vertically depending stops 130 and 130' 50 are provided, respectively, for the inner ends of the tracks 125 and 125' for limiting the inward travel of the hangers 124 and 124'.

For enabling disengagement of the hangers 124 and 124' from the auxiliary boat, the 55 outer ends of the tracks 125 and 125' terminate, respectively, some distance inside of the outer limit of travel of the hangers 124 and 124', and auxiliary tracks 131 and 131' are arranged for receiving, respectively, the hangers 124 and 124' beyond the ends of the 60 tracks 125 and 125'.

The auxiliary tracks 131 and 131' are oscillatably mounted at their outer ends on 65 horizontal pivot pins 132 and 132', respectively, carried by the keel of the auxiliary boat.

Inwardly spaced from the pivot pins 132 and 132', screws 133 and 133', respectively, 70 are operatively mounted in threaded aper-

tures in flanges 134 and 134' mounted within the auxiliary boat 21.

The lower ends of the screws 133 and 133' are rotatably connected, respectively, in suitable slotted apertures with the tracks 131 and 131', and the upper ends of the screws 133 and 133' within the boat 21 are provided with suitable hand wheels 135 and 135', respectively, for turning the screws, whereby the screws may be raised and lowered, and the auxiliary tracks 131 and 131' may be oscillated about the horizontal pivots 132 and 132', respectively, for lowering or raising the inner ends of the tracks 131 and 131' into or out of prolongation of the tracks 125 and 125', respectively. 75

Accordingly, when the screws 133 and 133' are elevated, the hangers 124 and 124' are supported in any position of their travel to or away from the strut 113, as may be determined by the raising or lowering of the strut 113. 80

When the hitch 112 as above described, is in the lowered position illustrated in Fig. 16, it operates to keep the auxiliary boat on an even keel, by bracing the keel longitudinally against the taut cable. 85

Then the hitch is in the position illustrated by the dot and dash lines in Fig. 16, or by full lines in Figs. 6, 8 and 11, turning the screws 133 and 133' to lower them, will lower the inner ends of the auxiliary tracks, 125 and 125' whereby the hangers 124 and 124' will drop therefrom. 95

Likewise by turning the rod 127 for lowering it, the jaws 117 and 117' will be disengaged from the pin 120, whereby the hitch will be entirely disengaged from the auxiliary boat. 100

For entirely releasing the connection between the auxiliary boat and the submarine, there remains only to release the connector 66 as aforesaid, and to drop the sleeve 106 from the cylinder 107. 105

The submarine 10 being submerged and being connected as aforesaid with the auxiliary submarine boat 21 by the extensible and retractable cable connecting member 54, and the auxiliary boat 21 being secured in the dock 11 as illustrated in Figs. 1, 3, 6, 7, 8, 9, 10, 11, and 16, and the closed dock being evacuated of water, the auxiliary boat may be manned by a part of the submarine's crew leaving the submarine through the door 15 and entering the auxiliary boat through the door 46. 110

Both doors 15 and 46 may then be closed, and the valve 50 may be opened permitting entrance of water through the conduit 49 into the dock 11, and the screws 27 may be withdrawn from engagement with the seats 20, and the jack screws 42 may be turned to raise the auxiliary boat and break its water-sealed closure with the dock, whereby water will rush into the dock 11, and the natural 125

buoyancy of the auxiliary boat 21 will cause it to rise to the surface, the cable connector 54 being paid out from the drum 78 as the auxiliary boat rises, and the hitch 112 tending to keep the auxiliary boat on an even keel as aforesaid.

With the auxiliary boat thus having risen to the surface, and being connected by the composite cable 54 with the submerged submarine 10, the maneuvering, torpedo fire, and other operations of the submarine, may 10 be controlled and directed from the auxiliary boat.

If it is desired that the auxiliary boat 21 perform an independent mission, the connector 66 and the hitch 112 are released as aforesaid from the auxiliary boat before the auxiliary has been released from the dock.

After the auxiliary boat has completed its 20 mission, the submarine may arise to just below the surface as illustrated in Fig. 2, and move slowly ahead, whereby the auxiliary boat moving at a faster speed may come up from the rear and direct its prow into the bumper, from which position it may be redocked by bringing the submarine further to the surface so that the dock 11 closes about the auxiliary boat 21 from below.

When the auxiliary boat is connected by 30 the cable 54, it may be redocked either by being drawn down to the submerged submarine, or by the submarine rising to the boat.

I claim:

1. A submarine, an auxiliary boat, an extensible and retractable connecting member 35 between the boat and the submarine, means operable from within the boat for detaching the boat from the member, means in the submarine for extending and retracting the connecting member into and out of the submarine, and a water seal on the submarine about the connecting member, and the connecting member including an electrical conductor for connecting electrical apparatus in the 40 boat and electrical apparatus in the submarine.

2. A submarine, a dock therein, an auxiliary boat, an extensible and retractable connecting member between the boat and the 50 submarine, and means facilitating maneuvering the boat into and out of the dock, including a yielding bumper extending outwardly from the submarine.

3. A submarine, a dock therein, an auxiliary boat, an extensible and retractable connecting member between the boat and the submarine, and means facilitating maneuvering the boat into and out of the dock, including a yielding V bumper extending outwardly from the submarine.

4. A submarine, an auxiliary boat, an extensible and retractable connecting member between the boat and the submarine, means in the submarine for extending and retracting 65 the connecting member into and out of

the submarine, a water seal on the submarine about the connecting member, and means for moving the extending and retracting means so that the connecting member will always be aligned with the water seal during 70 extension and retraction thereof.

5. A submarine, an auxiliary boat, an extensible and retractable connecting member between the boat and the submarine, and a stabilizing hitch operating between the connecting member and the boat and adjustable 75 from within the boat.

6. A submarine, an auxiliary boat, an extensible and retractable connecting member between the boat and the submarine, a stabilizing hitch operating between the connecting member and the boat, and means operable from within the boat for detaching the hitch from the boat.

7. A submarine, an auxiliary boat, an extensible and retractable connecting member between the boat and the submarine, a stabilizing hitch operating between the connecting member and the boat, and means operable from within the boat for detaching the 85 hitch and the member from the boat.

8. A submarine, a dock therein, an auxiliary boat, an extensible and retractable connecting member between the boat and the submarine, yielding bumper means facilitating maneuvering the boat into and out of the dock, and an adjustable stabilizing hitch operating between the connecting member and the boat.

In testimony that I claim the above, I have 100 hereunto subscribed my name.

EDWARD J. SHOEMAKER.
